N. TERRY.
AEROPLANE STABILIZER OR CONTROL.
APPLICATION FILED MAR. 29, 1915.

Patented Feb. 6, 1917.

UNITED STATES PATENT OFFICE.

NERI TERRY, OF HARDISTY, ALBERTA, CANADA.

AEROPLANE STABILIZER OR CONTROL.

1,214,612.

Specification of Letters Patent.

Patented Feb. 6, 1917.

Application filed March 29, 1915. Serial No. 17,879.

To all whom it may concern:

Be it known that I, NERI TERRY, a subject of the King of Great Britain, and resident of Hardisty, in the Province of Alberta, Dominion of Canada, have invented certain new and useful Improvements in Aeroplane Stabilizers or Controls, of which the following is the specification.

This invention relates to aeroplanes and particularly refers to improvements in stabilizers or control devices therefor and the objects of the invention are to prevent the machine becoming unduly tilted laterally or longitudinally and to automatically return the machine to its normal horizontal position, to render the stabilizers capable of being manually operated, to simplify the construction and generally adapt the several parts to better perform the several functions required of them.

The invention consists essentially of the improved stabilizers particularly described and set forth in the following specification and accompanying drawings forming part of the same.

In the drawings, Figure 1 is a perspective view of an aeroplane embodying the present invention. Fig. 2 is a front elevation of the pilot seat showing the control levers mounted thereon. Fig. 3 is a perspective view of the bolt adapted to lock the seat in a fixed position.

Like characters of reference refer to like parts in the several drawings.

Referring to the drawings, A represents an aeroplane of any usual construction comprising the fusilage 1 and the upper and lower planes 2 and 3, such aeroplane being provided with the usual prime mover and not forming part of the present invention except in so far that the stabilizer B is mounted thereon it is deemed unnecessary to further describe the same.

The stabilizer comprises auxiliary planes 4 and 5 pivotally mounted in front of their center of pressure to the upper plane 2 and adapted to be rotated in a vertical plane as the aeroplane is laterally tilted.

Pivots supported from the upper plane 2 is the pilot seat 6 having the transversely extending rod 7 rigidly mounted on the bottom thereof and carrying brackets 8 and 9, the object of which will be made clear hereafter.

Pivots mounted intermediate of the standards 10 extending between the upper

and lower planes 2 and 3 are spindles 11 and 12 carrying intermediate of their ends bell cranks 13 and 14, the horizontal arms of which are pivotally connected by means of the links 15 and 16 to the auxiliary planes 4 and 5, the vertical arms of the said bell cranks being connected by means of the links 17 and 18 to the levers 19 and 20 pivotally mounted on the rod 7 and provided with spring controlled detents adapted to engage with the brackets 8 and 9.

The tail 21 of the aeroplane is pivotally mounted in front of the center of pressure to the fusilage 1 and is adapted to be rotated in a vertical plane, to which end it is provided with an eye bolt 22 connected to one end of the link 23, the opposite end of which is attached to the lever 24 pivotally mounted to the chair and provided with a spring controlled detent adapted to engage with the quadrant 28 thereby permitting of the tail being fixed in any desired position relating to the pilot's seat and be manually operated if desired.

Located below the chair is a spring controlled locking bolt 25 mounted in any convenient manner to the fusilage 1 and adapted to be depressed by the foot of the pilot to which end the lever 26 is provided, pivotally mounted at one end to the fusilage, the other end carrying a pin adapted to engage with the said locking bolt which when depressed is secured in position by the catch member 27.

It will be clear that in the operation of the device should the aeroplane become tilted the pilot's seat 6 will swing about its upper pivoted end, the motion being transmitted through the links 17 and 18 to the bell cranks 13 and 14 which in turn through the links 15 and 16 rotate the auxiliary planes 4 and 5 in a vertical plane so increasing the lifting power on the depressed side of the machine and reducing the lifting power on the elevated side of the machine, thereby tending to bring the machine back into a normal horizontal position. Should the machine tilt in a longitudinal direction the seat will again swing about its upper pivoted point, the motion being transmitted to the tail 21 through the medium of the link 23 thereby increasing or decreasing the lifting power and tending to bring the machine to a normal horizontal position.

When the pilot's seat 6 is fixed relatively to the fusilage 1 by means of the locking bolt

25 which engages the bottom of the said seat, the auxiliary planes 4 and 5 and the tail 21 are capable of being manually operated by the levers 19, 20 and 24 to increase or decrease the lifting power of the aeroplane on any side found necessary.

From this description it will be seen that I have invented a stabilizer which can be conveniently adapted to aeroplanes and the like, which will cause the machine to automatically assume a normal horizontal position when tilted either transversely or longitudinally.

As many changes could be made in the 15 above construction and many apparently widely different embodiments of my invention, within the scope of the claim, constructed without departing from the spirit or scope thereof it is intended that all matter contained in the accompanying specifica- 20

tion and drawings shall be interpreted as illustrative and not in a limiting sense.

What I claim as my invention is:

In an aeroplane, pivotally mounted auxiliary planes, a pivotally mounted seat, 25 means connecting the seat and auxiliary planes consisting of link and bell crank mechanism adapted to automatically actuate said planes when the seat is oscillated, means for securing the seat in a rigid position and 30 manually operating levers pivotally attached to the seat coacting with the link mechanism and adapted to actuate the auxiliary planes when the seat is rendered rigid.

In witness whereof I have hereunto set 35 my hand in the presence of two witnesses.

NERI TERRY.

Witnesses:

FRANK E. BUTALL,
C. IAN BAZALGETTE.
